CLAIM

The ornamental design for an air deflector for vans and similar vehicles, as shown.

DESCRIPTION

FIG. 1 is a right side, rear perspective view of an air deflector for vans and similar vehicles showing my new design with a van shown in broken lines for illustrative purposes only;

FIG. 2 is a rear elevation view thereof;

FIG. 3 is a left side elevation view thereof;

FIG. 4 is a front elevation view thereof; and

FIG. 5 is a bottom plan view thereof.
